UNITED STATES PATENT OFFICE.

MARY B. DUNAGAN, OF PORTLAND, OREGON.

HOSE-SUPPORT.

1,110,753.

Specification of Letters Patent. Patented Sept. 15, 1914.

Application filed January 30, 1913. Serial No. 745,279.

To all whom it may concern:

Be it known that I, MARY B. DUNAGAN, citizen of the United States, residing at Portland, in the county of Multnomah and 5 State of Oregon, have invented certain new and useful Improvements in Hose-Supports, of which the following is a specification.

This invention relates to improvements in hose supporters, and has for one of its objects to simplify the construction and increase the efficiency and safety of devices of 10 this character.

Another object of the invention is to provide a simply constructed device in which 15 the hose or other garment is firmly locked in position within the holder and prevented from accidental displacement while at the same time readily releasable when required.

Another object of the invention is to provide a simply constructed device which may 20 be applied without material structural change to hose supporters of various forms.

With these and other objects in view the invention consists in certain novel features 25 of construction as hereinafter described and then specifically pointed out in the claim, and shown in the drawings illustrative of the preferred embodiment of the invention.

Figure 1 is a front elevation of the 30 improved device. Fig. 2 is a side elevation of the same. Fig. 3 is a section on the line 3—3 of Fig. 1. Fig. 4 is a perspective view of the locking tongue from the rear.

Corresponding and like parts are referred 35 to in the following description and indicated in all the views of the drawings by the same reference characters.

The improved device comprises a loop 40 represented as a whole at 10 and with a contracted lower portion 11 and a laterally enlarged portion 12 intermediate the ends and with a closed loop 13 for receiving the suspending member. The loop 10 is provided with a transverse member 14 intermediate 45 the ends, and mounted to swing at 15 upon the cross member 14 is a locking tongue 16, preferably of resilient material, and firmly held by the pivot 15 from movement toward or away from the loop. At its free end the 50 tongue 16 is provided with a longitudinally extending projection or "hump" 17 at the inner side, forming a tooth, and with a finger engaging enlargement 18 at the outer side. The tongue 16 is of sufficient length 55 and width to extend partly over the contracted portion 11 of the loop as represented

in Fig. 1, with the hump or projection 17 between the sides of the contracted portion of the loop. The projection 17 is formed with angular sides so that it can be forced over the side members of the loop when a sufficient force is imparted to the tongue, and thus "sprung" into position between the side members of the loop, and form a partial closure to the contracted portion 11 60 of the loop. The tongue 16 is of sufficient strength to resist any normal strains to which it will be subjected when in use, while at the same time will yield when abnormal lateral strain is applied to cause the tongue 16 to be swung to the right or left upon its pivot 15. Attention is also called to the fact that when the tongue 16 is moved to position to engage the garment, as particularly shown in Fig. 3 of the drawing, in 70 which position of the tongue, the tooth 17 is disposed between the side portions of the loop 10, that said tongue is held from lateral displacement by said side portions, the side portions being arranged to contact with the tooth 17 to thus securely maintain the adjacent extremity of the tongue in operative 75 engagement with the garment. It will also be noted that the inclined faces of the tooth 17 provide a relatively sharp edge at its 80 outer extremity, which will bite into the portion of the garment engaged by the support, when the tongue is moved to operative position so that said tooth will effectually 85 engage the garment to maintain the support 90 in engagement therewith.

Associated with the loop is a flexible member 19, preferably of suitable fabric, and connected to the member 19 at its free end is a button 20, the button including a reduced shank 21 adapted to enter the contracted portion 11 of the loop, while the button portion is adapted to pass through the enlarged portion 12 of the loop. The member 19 is of sufficient length so that 95 when the button is inserted through the enlarged portion 12 of the loop and passed into the reduced portion 11 of the loop, the member 19 will be stretched relatively taut 100 rearwardly of the loop, and the tongue 16 is of sufficient length so that when disposed in position substantially in parallel relation to the longitudinal plane of the loop the free end of the tongue will extend toward the enlarged head portion of the button and in close proximity thereto. By this 105 simple means it will be obvious that when 110

the tongue 16 has been turned to one side and the button 20—21 inserted into its seat within the contracted portion 11, and the tongue forcibly moved into position substantially in parallel relation to the longitudinal plane of the loop with the projection or hump 17 located within the contracted portion 11, the button will be firmly held in position and prevented from displacement so long as the tongue remains in closed position relative to the loop.

In applying the improved device the member 19 together with its button is placed internally of the hose or other garment to be held and the loop 10 disposed externally of the garment. The button 20 with the portion of the garment which is opposite the button is then forced through the enlarged portion 12 and into the contracted portion, the portion of the garment which is engaged by the button passing with the same into the contracted portion of the loop, while the widened portion of the tongue bears over the contiguous portions of the loop and thus materially increases the "grip" between the parts. The tongue 16 is then forced into its holding position, as shown in Fig. 1, and effectually prevents the accidental displacement of the button.

The improved device is simple in construction, can be inexpensively manufactured and applied and firmly locks and holds the hose or other garment and prevents accidental displacement or loosening of the same.

The device may be manufactured of any required material and of any required size and adapted to all the various uses of a hose supporter or like device.

In practice an elastic strap 22 is employed and coupled to the flexible loop 13 by a con-

ventional buckle 23 of the ordinary type, and the member 19 is preferably connected at one end to the member 22, but it will be understood that the improved device is not necessarily limited to any specific arrangement of the parts other than the loop 10 and the tongue 16, as various modifications and changes in construction within the scope of the claim may be made without departing from the principle of the invention or sacrificing any of its advantages.

Having thus described the invention what is claimed is:

A device of the character described including a loop having spaced side portions and formed with a restricted neck portion, a button arranged for engagement by said neck portion, a relatively wide locking tongue pivotally connected to the loop opposite the neck portion, and a longitudinally extending tooth formed on the inner face of the tongue adjacent the free extremity thereof, said tooth being provided with oppositely inclined faces and when the tongue is in locking position being disposed between the side portions of the loop in the path of the button and held by said side portions from lateral movement, said oppositely inclined faces being adapted to ride over the side portions of the loop when the tongue is manually turned and providing a relatively sharp edge at the inner extremity of the tooth adapted to bite into the adjacent portion of a fabric engaged by the button.

In testimony whereof I affix my signature in presence of two witnesses.

MARY B. DUNAGAN. [L. S.]
